GAS ASSIST SYSTEM FOR RECOIL ACTUATED
FIREARMS

Earle M. Harvey, Agawam, Mass., assignor to the United States of America as represented by the Secretary of the Army

Filed Apr. 5, 1962, Ser. No. 185,486

2 Claims. (Cl. 89—159)

(Granted under Title 35, U.S. Code (1952), sec. 266)

The invention described herein may be manufactured and used by or for the Government for governmental purposes without the payment to me of any royalty thereon.

This invention relates to machine guns and more particularly to the means for energizing the operating mechanisms of machine guns for automatic operation.

It is well known in the art that the recoil systems for gun operation have certain advantages over those systems which utilize gas pressure. But when the cartridges to be fired are of low-energy types, the recoil force created in the barrel by discharge of the cartridges is oftentimes insufficient to energize the gun's operating mechanism. Therefore, an assist must be provided by adding a booster which utilizes gas pressure to impart additional energy to the barrel.

These boosters are conventionally mounted on the front end of a barrel jacket which is fixed to the gun receiver so as to inclose the barrel. The discharge gases are partially intercepted by an annular pocket in the booster so as to act rearwardly against the front end of the barrel to supplement the recoil energy transferred thereto. These boosters, which require the support of a barrel jacket, make it difficult and generally impossible to mount a front sight and other accessories on the muzzle of the gun. Moreover, these boosters have a tendency to be fouled by copper and carbon build-up to the extent that the barrel is blocked against reciprocation.

In the application for a "Machine Gun Selectively Operated by a Gas or Recoil System," Serial No. 185,485, filed April 5, 1962 by John L. Lochhead, there is taught a machine gun which is selectively operated by either a gas system or a recoil system. However, when the cartridges utilized by such gun are of low-energy types, the recoil force imparted to the barrel is insufficient to operate the gun. Consequently, gas assist must be provided. The conventional gas booster is not practical with this gun, which is adaptable for hand firing, because a barrel jacket would add to the weight and the bulk of the weapon and would interfere with the mounting of a first sight and other accessories on the muzzle end of the barrel.

It is, therefore, one object of this invention to provide for such recoil-operated guns a gas assist device which will not interfere with the installation of a sight or other accessory on the front end of the gun barrel.

It is another object of this invention to provide such a gas assist device which will bleed gases from the gun barrel midway along the length thereof where the gases are the hottest to reduce considerably any build-up of copper and carbon deposits.

It is a further object of this invention to enlarge the scope of the aforementioned machine gun by adapting it for use with cartridges which are of low-energy types.

The specific nature of the invention as well as other objects and advantages thereof will clearly appear from a description of a preferred embodiment as shown in the accompanying drawings in which:

FIG. 1 is a partially cross-sectioned side view of the rear portion of the machine gun with the bolt in battery position;

FIG. 1a is a forward continuation of FIG. 1 and shows the selector indexed in position for operation of the machine gun by gas means;

2

FIG. 2 is an elevational view of the front portion of the receiver showing the selector indexed for gas operation of the machine gun and the barrel in the battery position;

FIG. 3 is a longitudinally cross-sectioned view of the rear portion of the machine gun and shows the bolt in recoil position;

FIG. 4 is a view taken along line 4—4 of FIG. 2;

FIG. 5 is a view taken along line 5—5 of FIG. 4;

FIG. 6 is a view taken along line 6—6 of FIG. 4;

FIG. 7 is a forward extension of FIG. 3 and shows the selector indexed in position for operation of the machine gun by gas assist recoil means;

FIG. 8 is a view similar to FIG. 2 but showing the selector indexed for gas assist recoil operation of the machine gun and the barrel in the driving position;

FIG. 9 is a view taken along line 9—9 of FIG. 8;

FIG. 10 is a view taken along line 10—10 of FIG. 9;

FIG. 11 is a view taken along line 11—11 of FIG. 9; and

FIG. 12 is an exploded perspective view of the selector.

Shown in the figures is a machine gun 12 which is selectively operable by gas pressure or recoil forces such as is disclosed in the application for a "Machine Gun Selectively Operated by a Gas or Recoil System," Serial No. 185,485, filed April 5, 1962 by John L. Lochhead. Machine gun 12 is adapted for automatically firing a small caliber cartridge 14 which is of 7.62 caliber, or the like, and includes a receiver 16 in which a bolt assembly 18 is mounted for sliding reciprocation between a forward locked position and a rearward recoil position. A barrel assembly 20 is journaled in the front end of receiver 16 for longitudinal reciprocation between a forward battery position and a rearward driving position.

Barrel assembly 20 includes a barrel 22, the front portion of which extends forwardly from receiver 16, and a gas cylinder assembly 24 which includes a gas cylinder 26 and a cooperating piston 28. Gas cylinder 26 includes a central body portion 29 which is bracketed to barrel 22 approximately midway the length thereof so that the gas cylinder is located within receiver 16. A cylindrical hole 30 extends laterally through body portion 29 and communication is provided between such hole and bore 31 of barrel 22 by a vertical passageway 32. Piston 28 is slidably mounted in a bore 34 which extends forwardly in gas cylinder 26 from the rear end thereof to an end wall 36 located rearwardly of hole 30. A gas port 40 extends forwardly from end wall 36 so as to provide communication between bore 34 and hole 30.

Extending integrally forward from body portion 29 is a cylindrical piston portion 42 which is smoothly machined around the outside. A concentric bore 44 extends forwardly through piston portion 42 from hole 30 and such piston portion is received by a mating chamber 46 in a cylinder block 48 which is fixed to receiver 16. A close sliding fit is provided between piston portion 42 and the wall of chamber 46 so as to eliminate as much as possible gas leakage thereby. If necessary, gas seal rings can be installed on piston portion 42.

A selector 50 is rotatably received by a hole 30 so as to be selectively indexed in a "Gas" position or a "Recoil" position. Selector 50 includes a cylindrical rod 52 received by hole 30 and such rod extends from opposite sides of body portion 29 to form an extending end 54 on the left side of gas cylinder 26 and another extending end 56 on the right side thereof. Provided in rod 52 is a first aperture 58 and a second aperture 60 which are radially disposed 90° apart so as to converge at the center of the rod.

When selector 50 is indexed in the "Gas" position, first aperture 58 is in registry with gas port 40 and second aperture 60 is in registry with passageway 32 so that discharge gases are directed from bore 31 of barrel 22 to bore 34 to act upon piston 28. When selector 50

is indexed in "Recoil" position by 90° rotation of the selector in a clockwise direction, looking towards the right side of machine gun 12 and as shown in FIG. 1a, first aperture 58 is in registry with passageway 32 and second aperture 60 is in registry with bore 44 so that discharge gases are directed from bore 31 of barrel 22 into chamber 46.

Extending end 54 on the left side of selector 50 is slabbed off at diametrically opposed sections to form an ear 62 which is symmetrical to the lateral plane which is coincident with the main axis of first aperture 58. When selector 50 is indexed in the "Recoil" position so that the longest axis of ear 62 is longitudinally disposed, the ear is receivable by a mating longitudinally disposed channel 64 in receiver 16 and is slidable along the channel during reciprocation of barrel assembly 20 to and from the driving position. Channel 64 has a width similar to the short axis of ear 62 and is interrupted by an oval recess 66 which is located so as to be in registry with selector 50 when barrel assembly 20 is in the forward battery position. Recess 66 has a radius similar to that of rod 52 so that the selector is free to be rotated between the "Gas" and "Recoil" positions when barrel assembly 20 is in battery position.

Extending end 56 on the right end of selector 50 extends through receiver 16 and provided on such extending end is a button 68 which provides means for manually rotating the selector. Extending end 56 is interrupted by a pair of diametrically opposed segmental cuts 70 which form a key section 72 which is coincidental with the same lateral plane as ear 62. Key section 72 is slidably receivable by a slot 74 in the right side of receiver 16 to permit reciprocation of barrel assembly 20 when the long axis of the key section is in alignment with such slot. The width of slot 74 is similar to the short axis of key section 72 and such slot is interrupted by a circular orifice 76 which is arranged to be in registry with selector 50 when barrel assembly 20 is in battery position and which has a radius similar to that of rod 52. Thus, when selector 50 is in "Recoil" position, key section 72 is in alignment with slot 74 and ear 62 is in alignment with channel 64 so that barrel assembly 20 is free to reciprocate between the battery and driving positions. When selector 50 is rotated to the "Gas" position so that the long axes of ear 62 and key section 72 are vertically disposed, barrel assembly 20 is blocked in battery position because of the cooperation of the ear with the walls of recess 66 and of the key section with the wall of orifice 76.

As disclosed in the aforementioned patent application, bolt assembly 18 includes a carrier 80, a bolt 82, which is mounted thereon for relative rotational and longitudinal displacement, and cam means 84 operationally disposed between the carrier and bolt for converting relative longitudinal displacement of the bolt and carrier to rotational displacement of the bolt so that the bolt is locked to the barrel during forward displacement of the carrier relative to the bolt and is unlocked during rearward displacement of the carrier relative to the bolt. An accelerator 86 is pivotally mounted in receiver 16 and is arranged according to conventional design to accelerate bolt assembly 18 to the rearward recoil position when barrel assembly 20 is adjacent its driving position. A driving rod 88 extends forwardly from carrier 80 so as to be contactable by piston 28 to transfer the energy applied thereto by gases bled from the bore of barrel 22 to the carrier.

Thus, when machine gun 12 is to be operated by gas means, selector 50 is indexed in the "Gas" position, which is identifiable by the marking of "Gas" on the right side of receiver 16 and an arrow on button 68. With selector 50 in the "Gas" position, ear 62 and key section 72 are positioned in recess 66 and orifice 76, respectively, to block displacement of barrel assembly 20 from battery position and first aperture 58 is in registry with gas port 40 and second aperture 60 is in registry with passageway

32 so that discharge gases are transferable from the bore of barrel 22 into bore 34 to act against piston 28.

When machine gun 12 is to be operated by recoil energy in barrel assembly 20, selector 50 is indexed in the "Recoil" position which is identifiable by the marking of "Recoil" on the side of receiver 16 and an arrow on button 68. With selector 50 in the "Recoil" position, ear 62 and key section 72 are respectively aligned with channel 64 and slot 74 so as to be receivable thereby and, consequently, barrel 20 is free to reciprocate to and from driving position. Also, first aperture 58 is in registry with passageway 32 and second aperture 60 is in registry with bore 44 so that, when cartridge 14 is discharged in barrel 22, barrel assembly 20 is energized by the recoil forces and, when the projectile of the cartridge passes through bore 44 into chamber 46. The gases received by chamber 46 add to the recoil energy in barrel assembly 20 so that sufficient energy is imparted thereto to drive bolt assembly 18 to the recoil position and perform its operating functions.

From the foregoing it is clearly apparent that there is provided herein for recoil operated firearms a gas assist system which is ideally suited to those firearms which are hand fired as the device adds little weight and bulk to the firearms and the muzzle end of the barrel is free for the mounting of accessories thereon. Moreover, the gas assist system is an improvement over conventional booster devices as it is not subjectable to copper and carbon build-up.

Although a particular embodiment of the invention has been described in detail herein, it is evident that many variations may be devised within the spirit and scope thereof and the following claims are intended to include such variations.

I claim:

1. A machine gun including a receiver, a barrel journaled in said receiver so as to be movingly responsive to recoil energy produced in said barrel by discharge of a cartridge therein, a bolt assembly mounted in said receiver for reciprocation therein, accelerator means for transferring energy from said barrel to said bolt assembly for reciprocation thereof, a gas cylinder fixedly mounted on said barrel, a passageway arranged between said gas cylinder and said barrel for bleeding gases therefrom into said gas cylinder, and means disposed in cooperation with said gas cylinder for selectively blocking said barrel against displacement and utilizing the gases bled from said barrel to energize said bolt assembly for reciprocation and for selectively releasing said barrel for reciprocation and utilizing the gases bled from said barrel for supplementing the recoil energy in said barrel to provide sufficient energy in said barrel for reciprocating said bolt assembly when transferred thereto by said accelerator means.

2. A machine gun including a receiver, a bored barrel journaled in said receiver so as to be movingly responsive to recoil energy produced in said barrel by discharge of a cartridge therein, a bolt assembly mounted in said receiver for reciprocation therein, accelerator means mounted in said receiver so as to transfer energy from said barrel to said bolt assembly for reciprocation thereof, a gas cylinder fixedly mounted on said barrel, a passageway arranged between said gas cylinder and said barrel for bleeding gases therefrom into said gas cylinder, a bore in said gas cylinder, a piston slidably mounted in said bore and arranged to be actuatable against said bolt assembly by gases received by said bore, a hollow piston portion on said gas cylinder, a cylinder block fixed to said receiver and provided with a chamber for slidably receiving said piston portion, a hole extending laterally through said gas cylinder, conduit means extending between said hole and the inside of said barrel, between said hole and said bore in said gas cylinder and between said hole and the inside of said piston portion, a selector mounted in said hole for rotation between a first position

and a second position, aperture means arranged in said selector completing communication between said barrel and said bore in said gas cylinder for passage of gases thereinto when said selector is in said first position and for completing communication between said barrel and the inside of said piston portion when said selector is in the second position, and cooperating means in said selector and said receiver for blocking displacement of said barrel

when said selector is in the first position and for releasing said barrel for displacement when selector is in the second position.
